(57) **CLAIM**

The ornamental design for a floor tray, as shown and described.

DESCRIPTION

FIG. 1 is a top, rear, right side perspective view of a design for a floor tray;

FIG. 2 is a top view of the design of FIG. 1;

FIG. 3 is a bottom view of the design of FIG. 1;

FIG. 4 is a left side view of the design of FIG. 1;

FIG. 5 is a right side view of the design of FIG. 1;

FIG. 6 is a front view of the design of FIG. 1;

FIG. 7 is a rear view of the design of FIG. 1; and,

FIG. 8 is a top, front, left side perspective view of the design of FIG. 1.

Broken lines illustrate boundaries of the claimed design and environmental subject matter outside thereof, and form no part of the claimed invention.
